UNITED STATES PATENT OFFICE

107,737

DESIGN FOR A SMOCK

Jack Wien, Kansas City, Mo.

Application June 21, 1937, Serial No. 69,954

Term of patent 3½ years

To all whom it may concern:

Be it known that I, Jack Wien, a citizen of the United States, residing at Kansas City, in the county of Jackson and State of Missouri, have invented a new, original, and ornamental Design for a Smock, of which the following is a specification, reference being had to the accompanying drawing, forming a part thereof.

Fig. 2 is a back view of the same, and, Fig. 3 is an enlarged, fragmentary view illustrating one of the decorative details.

I claim:

The ornamental design for a smock, as shown and described.

JACK WIEN.
